BASKET FOR HOLDING CALLING CARDS OR THE LIKE

Albert N. Brooks, Chicago, Ill.

Application November 10, 1953, Serial No. 27,537

Term of patent 7 years

(Cl. D58—4)

To all whom it may concern:

Be it known that I, Albert N. Brooks, a citizen of the United States and a resident of Chicago, in the county of Cook and State of Illinois, have invented a new, original, and ornamental Design for a Basket for Holding Calling Cards or the like, of which the following is a specification, reference being had to the accompanying drawing forming part thereof.

Fig. 1 is a side view of a basket for holding calling cards or the like showing my new design;

Fig. 2 is a front view thereof;

Fig. 3 is a top view thereof.

I claim:

The ornamental design for a basket for holding calling cards or the like, substantially as shown.
